Primary Examiner — Mark Goodwin(74) *Attorney, Agent, or Firm* — Michael J. Striker(57) **CLAIM**

The ornamental design for a vehicle crawler mechanism, as shown and described

DESCRIPTION

FIG. 1 is a perspective view of a vehicle crawler mechanism as shown and described;

FIG. 2 is a front view thereof;

FIG. 3 is a top view thereof; and,

FIG. 4 is a side view thereof which is a mirror image of the opposite side view thereof.

The portions of the vehicle, crawl or mechanism shown in broken lines form no part of the claim design.
